UNITED STATES PATENT OFFICE.

HAROLD C. BRECKENRIDGE, OF CLANCY, MONTANA.

ELECTRIC LANTERN.

1,319,638.

Specification of Letters Patent.

Patented Oct. 21, 1919.

Application filed July 19, 1918. Serial No. 245,700.

To all whom it may concern:

Be it known that I, HAROLD C. BRECKENRIDGE, a citizen of the United States, residing at Clancy, in the county of Jefferson 5 and State of Montana, have invented new and useful Improvements in Electric Lanterns, of which the following is a specification.

This invention relates to electric lanterns 10 and it consists in the novel features herein-after described and claimed.

An object of the invention is to provide a lantern of the character stated which is of simple and durable structure and which includes a battery receptacle with a frame located below the same and a bulb positioned below the receptacle and disposed within the frame whereby it is protected by the same. An additional advantage of this arrangement is that the rays of light from the bulb may descend in a downward direction when the lantern is supported at a relatively high point and the bulb may be visible when the frame of the lantern is resting upon a 25 flat surface.

Another object of the invention is to so construct and arrange parts of the lantern that the battery may rest directly upon the upper portion of the frame, consequently 30 the weight of the battery is borne by the frame and the receptacle which incloses the battery is not liable to be distorted out of its proper shape or position.

In the accompanying drawing:—

35 Figure 1 is a vertical sectional view of the lantern.

Fig. 2 is a plan of the lantern, the bail being omitted.

The lantern comprises a frame 1 which 40 may serve as a base for the structure and which is composed of strands of stout wire suitably connected together. The said frame in general side elevation is in the form of a truncated cone and the wires are spaced 45 from each other. A receptacle 2 of tin, iron or other suitable metal is mounted upon the upper portion of the frame 1 and the top parts of the frame pass transversely through the lower portion of the receptacle 2 as best 50 illustrated in Fig. 1 of the drawing. A socket member 3 is attached to the lower

end of the receptacle 2 and is located between the side members of the frame 1. A bulb 4 is screw-threaded in the socket member 3 in a usual manner. When the bulb 4 is 55 in position in the socket member 3 it is electrically connected with the receptacle 1 which in the present instance serves as the ground of an electric circuit. A cover 5 is provided for the receptacle 1. A terminal 6 is mounted on the cover 5 and a wire 7 passes through the cover and is connected with the terminal 6 and passes along the inner side of the receptacle 2 and through the bottom thereof and connects with the bulb 4 65 through the socket member 3 in a usual manner. A battery 8 is housed within the receptacle 2 and rests at its lower end upon the upper end of the frame 1. The terminal 9 of the battery 8 is electrically connected 70 with the receptacle 2 by means of a wire 10. The terminal 11 of the battery 8 is electrically connected with a terminal 12 upon the cover 5 by means of a wire 13. A switch 14 is pivotally mounted upon the terminal 12 75 and may be swung into engagement with the terminal 6 hereinbefore described whereby electric circuit is closed. When the circuit is closed the bulb 4 is illuminated in a usual manner and when the switch 14 is moved 80 out of contact with the terminal 6 the circuit is broken and consequently the light at the bulb 4 is extinguished.

From the foregoing description taken in conjunction with the accompanying drawing 85 it will be seen that an electric lamp lantern of simple and durable structure is provided and that the bulb is so supported that the rays of light are not interfered with when the lantern is hanging upon a relatively high support. Also when the lantern is resting upon the base frame, the bulb is 90 visible.

Having thus described the invention what is claimed is:—

95 A lantern comprising a battery receptacle, a battery therein, a switch mounted on top of the receptacle, and controlling the battery current, a bulb carried by the bottom of the receptacle and arranged wholly beneath 100 the same, and in the battery circuit, and a supporting frame for the receptacle having

a height exceeding the projection of the bulb below the bottom of the receptacle, said frame comprising a base portion, upwardly and inwardly extending side members connected to the base portion, an upper bar formed integral with the side members, said upper bar passing transversely through

the wall of the receptacle immediately above the bottom thereof, and forming within the receptacle a means for supporting the battery. 10

In testimony whereof I affix my signature.

HAROLD C. BRECKENRIDGE.
